United States Patent Office

Des. 178,131
Patented June 26, 1956

178,131

DECANTER

Arnold I. Lorenzen, Toledo, Ohio, assignor to Owens-
Illinois Glass Company, Toledo, Ohio, a corporation of Ohio

Application September 17, 1953, Serial No. 26,852

Term of patent 14 years

(Cl. D58—6)

Fig. 5.

Fig. 1 is a front elevational view of a decanter showing my new design, the surface decoration shown being repeated on the opposite side;

Fig. 2 is a top plan view;

Fig. 3 is a sectional view taken along the line 3—3 of Fig. 1;

Fig. 4 is a sectional view taken along the line 4—4 of Fig. 1; and

Fig. 5 is a side elevational view.

I claim:

The ornamental design for a decanter, substantially as shown and described.
